Dennis I. McKenzie, Dayton, Ohio, assignor to
Moraine Box Company, Dayton, Ohio, a corpora-
tion of Michigan

Application February 17, 1948, Serial No. 8,790

7 Claims. (Cl. 229—14)

1

This invention relates to a structure for placement within a cardboard carton to reinforce the side walls of the carton, the cardboard carton providing means to retain the structure in assembled relationship, thereby providing a nailless shipping carton with a wooden crate reinforcement capable of being used for shipment of heavy articles.

An object of the invention is to provide a wooden crate type of reinforcement structure for placement within a cardboard carton which holds the structure together wherein the reinforcement structure is constructed and arranged in such a manner that metal straps can be placed around the cardboard carton to bind the parts of the reinforcement structure together.

It is still another object of the invention to provide a reinforcement structure in accordance with the foregoing object wherein reinforcing members extend longitudinally along the carton at each longitudinal corner thereof so that metal straps can be wrapped around the carton transversely thereof at any point between the ends.

Still another object of the invention is to provide a wooden crate type of reinforcement structure that is constructed and arranged in such a manner that the object to be carried can be placed upon a base or platform within a cardboard carton, the remaining side walls and top wall being insertable into the carton in locking arrangement with the base platform and with each other with reinforcing members extending longitudinally of the carton at each longitudinal corner thereof.

Still another object of the invention is to provide a crate type reinforcement structure of the kind referred to in the foregoing object wherein the walls of the structure are held together by cleats provided at the end walls of the structure so that a cardboard carton can be inserted over the assembled crate and slipped downwardly thereover, whereupon the carton and the assembled crate can be turned over completely to permit folding of the flaps over the open side of the carton. This latter arrangement provides for a structure wherein a heavy article can be assembled upon a base or platform and thereafter have the crate assembled around it whereupon the cardboard carton can be placed downwardly over the crate to hold the members of the crate in assembled relationship while the crate and the cardboard carton are being turned over to gain access to the flaps for closing the open side of the carton. The arrangement avoids the necessity of assembling the crate within a card-

2

board carton, at the same time permitting assembly of the crate around the object outside the carton, which can subsequently be placed around the assembled crate.

5 Further objects and advantages will become apparent from the drawings and the following description.

In the drawings:

10 Figure 1 is a perspective view of a reinforced cardboard carton embodying the features of this invention.

Figure 2 is a perspective view illustrating the cardboard carton in cross-section and the reinforcing frame or crate in elevation.

15 Figure 3 is a perspective elevational view of a crate type reinforcing structure for a cardboard carton wherein end cleats are used to hold the assembly together while the carton is being placed downwardly over the assembly and for holding the base platform to the assembly when the carton and the assembly are turned over.

20 Figure 4 is a perspective elevational view illustrating the device of Figure 3 in the turned-over position so that access is gained to the closing flaps of the cardboard carton for closing the open side thereof.

25 Figure 5 is a perspective elevational view of a portion of a crate type reinforcing structure such as that illustrated in Figure 3 incorporating a modified arrangement of the cleat assembly.

30 Figure 6 is a perspective elevational view illustrating a still further modified construction of the cleat assembly.

In this invention the crate type reinforcing structure consists of a base platform 10, a top platform 11 and side walls 12 and 13, as shown in Figure 2.

35 The base platform 10 consists of a pair of rails 15 and 16 that extend longitudinally of the carton into which the crate assembly will be placed. A pair of transversely extending rails 17 and 18 are positioned between the longitudinally extending rails 15 and 16, and suitably secured thereto. These transverse rails 17 and 18 have their ends 40 inset from the outer longitudinal edges 15a and 16a of the rails 15 and 16. A plurality of other transverse rails 19 can be provided between the rails 15 and 16 as desired to provide a base to which an object can be secured.

45 The top platform 11 is constructed in a manner like the base platform in that it is provided with a pair of side rails 20 and 21 that extend longitudinally of the carton into which the assembly is to be placed. The side rails 20 and 50 21 are secured together by the transversely ex-

tending rails 22 and 23 at opposite ends thereof. These rails 22 and 23 have their ends inset from the side edges 20a and 21a of the side rails 20 and 21.

The side walls 12 and 13 are constructed alike in that each of the side walls consist of a pair of vertically extending end rails 24 and 25. These end rails 24 and 25 are secured together by longitudinally extending rails 26 and 27. The rails 26 and 27 are inset from the ends of the vertically extending rails 24 and 25.

It will be noted that the rails 17, 18, 22 and 23 of the base platform 10 and the top platform 11 respectively are inset from the edges of the longitudinally extending rails 15, 16, 20 and 21 a distance equal to the thickness of the vertical rails 24 and 25. Also, it will be noted that the longitudinally extending rails 26 and 27 are inset relative to the ends of the vertical rails 24 and 25 a distance equal to the thickness of the transverse rails 17, 18, 22 and 23.

The above-mentioned construction provides for an inter-locking of the corners of the crate structure when it is in assembled condition, as shown in Figure 2. The construction is such that angular movement of the sides, top and base is prevented when the assembly is placed in the cardboard carton and straps placed around the outside of the carton in the manner shown in Figure 1.

In using the structure illustrated in Figure 2, the base platform 10 is first placed within the cardboard carton 30. The object is then placed upon the base, or it could be assembled to the base before being placed in the cardboard carton. The side walls 12 and 13 are then placed within the carton in their inter-locked relationship with the base platform 10. The top platform 11 is then placed within the carton in its inter-locked relationship with the side walls 12 and 13.

The flaps 30 and 31 of the carton can then be placed upon the top platform 11 to close the open side of the carton, and straps 32 placed around the complete assembly.

It will be noted that the straps can be placed around the carton transversely thereof at any position between the opposite ends of the carton, and when placed around the carton will hold the crate type reinforcing structure within the carton in secure inter-locked relationship.

The size or weight of many objects make it practically impossible to lift them into a cardboard carton. Thus, there is illustrated in Figs. 3 and 4 an arrangement of the reinforcing crate structure that is adapted to have an article mounted upon the base platform, the cardboard carton for enclosing the object and its crate being placed upon the crate from the top side. The top and bottom platforms of the crate structure are held together by cleat members so that after the cardboard carton is placed upon the crate, the entire box can be turned over without any danger of the base platform separating from the remaining crate structure. Thus, the article will be turned upside-down so that the open side of the cardboard carton can be closed, which side of the carton may be the bottom of the box for shipping purposes.

The crate structure of Figure 3 is constructed like the crate structure of Figure 2. Therefore, the parts of the crate of Fig. 3 that correspond to the parts of the crate of Fig. 2 are numbered with like numbers but advanced by 100. The description of the crate of Fig. 2 therefore applies to the description of the crate in Fig. 3.

The base platform 110 and the top platform 111 are prevented from separation from the side walls 112 and 113 by means of a cleat 150. The cleat 150 consists of a vertical rail 151 having crossbars 152 and 153 attached on each end thereof. The cleat 150 is positioned with the crossbars 152 and 153 in engagement with the outer faces of the base platform 110 and the top platform 111. One of these cleats is provided at each end of the crate structure, as illustrated in Fig. 3.

The transverse rails 117 and 118 of the base platform 110 and the transverse rails 112 and 113 of the top platform 111 are inset from the ends of the longitudinally rails to which they are attached to provide for the thickness of the vertical rail 151 of the cleat 150. Other than this slight modification the crate of Fig. 3 is identical with the crate of Fig. 2.

In using the crate illustrated in Fig. 3 the base platform 110 carries the object that is to be shipped, the object preferably being secured to the base platform. The side walls 112 and 113 are then moved into position on the base platform 110 and the top platform 111 moved into its position with the side walls 112 and 113. The end cleats 150 are then placed into position so that the assembled crate around the object appears as illustrated in Fig. 3.

The object will at this time be setting upright within the reinforcing crate. A cardboard carton 160 may then be slipped downwardly over the assembled crate. When this is done, the side walls of the crate in their assembled relationship and the cleats 150 will hold the base platform so that it cannot be separated from the remaining parts of the crate. The cardboard carton and the crate can then be turned over completely so that the flaps 161 of the open side of the cardboard carton will face upwardly as shown in Fig. 4. The flaps can then be closed and straps placed around the cardboard carton in the same manner as illustrated in Fig. 1.

In Figure 5 there is illustrated a modification of the structure of the crate shown in Fig. 3 wherein filler strips 170 are secured to the transverse rails 117 and 122 to provide a continuous edge along the transverse corners of the crate.

In Figure 6 there is illustrated a further modification of the crate structure wherein the transverse rails 117 and 122 are each provided with notches 201, 202 respectively to receive the cleats 150.

While the device disclosed and described herein illustrates preferable arrangements of the structure, yet modifications are possible without departing from the spirit of the invention, and those modifications that fall within the scope of the appended claims are intended to be included herein.

Having thus fully described my invention, what I claim as new and desire to secure by Letters Patent is:

1. A skeleton frame structure for placement in a container to support the walls thereof and consisting of, a bottom platform, a top platform and a pair of side walls extending between said platforms unsecured relative to each other, said top and bottom platforms each consisting of a pair of rails extending longitudinally of the structure and forming a corner edge of the same and a pair of rails extending transversely between said longitudinal rails at opposite ends thereof and secured thereto, said transverse rails having their ends inset from the longitudinal

edges of said longitudinal rails, said side walls extending between said top and bottom platforms with their longitudinal edges positioned in the recess provided by the inset ends of said transverse rails, and an unattached removable cleat T shaped at each end extending between said platforms at each end thereof with the T shaped ends projecting over each of said platforms to hold the same in their relative positions and having its outermost extremities contained within the skeleton frame structure as defined by planes across the outer surfaces of said top and bottom platforms and the ends of said longitudinally extending rails thereon.

2. A skeleton frame structure for placement in a container to support the walls thereof and consisting of, a bottom platform, a top platform and a pair of side walls extending between said platforms, said top and bottom platforms each consisting of a member extending longitudinally of the structure and forming a corner edge of the same and a second member extending transversely of said longitudinal member at opposite ends thereof and secured thereto, said second member having its ends inset from the longitudinal edges of said longitudinal member, said side walls extending between said top and bottom platforms with their longitudinal edges positioned in the recess provided by the inset ends of said second member, and an unattached removable channel-shaped cleat extending between said platforms at each end thereof having its opposite ends projecting over each said platform to hold the same in their relative positions and having its outermost extremities contained within the skeleton frame structure as defined by planes across the outer surfaces of said top and bottom platforms and the ends of said longitudinally extending rails thereon.

3. A skeleton frame structure for placement in a container to support the walls thereof and consisting of, a bottom platform, a top platform and a pair of side walls extending between said platforms unsecured relative to each other, said top and bottom platforms each consisting of a pair of rails extending longitudinally of the structure and forming a corner edge of the same and a pair of rails extending transversely between said longitudinal rails and secured thereto, said transverse rails having their ends inset from the longitudinal edges of said longitudinal rails, said side walls extending between said top and bottom platforms with their longitudinal edges positioned in the recess provided by the inset ends of said transverse rails with the outer faces of the said side walls flush with the outer edges of said longitudinal rails and with the ends of the side walls flush with the ends of said longitudinal rails.

4. A skeleton frame structure consisting of, a bottom platform, a top platform and a pair of side walls extending between said platforms unsecured relative to each other, said top and bottom platforms each consisting of a pair of rails extending longitudinally of the structure and forming a corner edge of the same and a pair of rails extending transversely between said longitudinal rails and secured thereto with the outer longitudinal edges flush with the ends of said longitudinal rails, said transverse rails having their ends inset from the longitudinal edges of said longitudinal rails, said side walls extending between said top and bottom platforms with their longitudinal edges positioned in the recess provided by the inset ends of said transverse rails

with the outer faces of the said side walls flush with the outer edges of said longitudinal rails and with the ends of the side walls flush with the ends of said longitudinal rails.

5. A skeleton frame structure for placement in a container to support the walls thereof and consisting of, a bottom platform, a top platform and a pair of side walls extending between said platforms unsecured relative to each other, said top and bottom platforms each consisting of a pair of rails extending longitudinally of the structure and forming a corner edge of the same and a pair of rails extending transversely between said longitudinal rails and secured thereto with the outer longitudinal edges flush with the ends of said longitudinal rails, said transverse rails having their ends inset from the longitudinal edges of said longitudinal rails, said side walls extending between said top and bottom platforms with their longitudinal edges positioned in the recess provided by the inset ends of said transverse rails with the outer faces of the said side walls flush with the outer edges of said longitudinal rails and with the ends of the side walls flush with the ends of said longitudinal rails, each of said side walls having a pair of rails extending longitudinally thereof inset from the longitudinal edges thereof and engaging the ends of said transverse rails to hold them between said last-mentioned rails and said first-mentioned longitudinal rails.

6. In combination, a container having non-self-supporting walls when placed under load of the article adapted to be carried therein, and a skeleton frame structure disposed therein consisting of a bottom platform, a top platform and a pair of side walls extending between said platforms unsecured relative to each other, said top and bottom platforms each consisting of a pair of rails extending longitudinally of the structure and forming a corner edge of the same and a pair of rails extending transversely between said longitudinal rails and secured thereto with the outer longitudinal edges flush with the ends of said longitudinal rails, said transverse rails having their ends inset from the longitudinal edges of said longitudinal rails, said side walls extending between said top and bottom platforms with their longitudinal edges positioned in the recess provided by the inset ends of said transverse rails with the outer faces of the said side walls flush with the outer edges of said longitudinal rails and with the ends of the side walls flush with the ends of said longitudinal rails, each of said side walls having a pair of rails extending longitudinally thereof inset from the longitudinal edges thereof and engaging the ends of said transverse rails to hold them between said last-mentioned rails and said first-mentioned longitudinal rails.

7. A skeleton frame structure for placement in a container to support the walls thereof and consisting of, a bottom platform, a top platform and a pair of side walls extending between said platforms, said top and bottom platforms each consisting of a pair of rails extending longitudinally of the structure and forming a corner edge of the same and a pair of rails extending transversely between said longitudinal rails and secured thereto, said transverse rails having their ends inset from the longitudinal edges of said longitudinal rails and their outer longitudinal edges flush with the ends of said longitudinal rails, said side walls extending between said top and bottom platforms with their longitudinal edges positioned in the recess provided by the inset ends of said

transverse rails with the outer faces of the side walls flush with the outer edges of said longitudinal rails and with the ends of the side walls flush with the ends of said longitudinal rails, and an unattached movable cleat T-shaped at opposite ends extending between said platforms at each end thereof with the T-shaped ends projecting over said platform to hold the same in their relative positions and having its outermost extremities contained within the skeleton frame structure as defined by planes across the outer surfaces of said top and bottom platforms and the ends of said longitudinally extending rails thereon.
